Primary Examiner — Susan E Krakower*Assistant Examiner* — Melissa A Santos(74) *Attorney, Agent, or Firm* — Justin Lampel(57) **CLAIM**

The ornamental design for a ceiling fan with light as shown and described.

DESCRIPTION

FIG. 1 is a perspective view of a ceiling fan with light showing my new design;

FIG. 2 is another perspective view thereof;

FIG. 3 is a front view thereof, with the back view being identical;

FIG. 4 is a left side view thereof, with the right side being identical;

FIG. 5 is a top plan view thereof;

FIG. 6 is a bottom plan view thereof; and,

FIG. 7 is a partial enlarged view of portion 9 in FIG. 1. The broken lines depict portions of the ceiling fan with light and form no part of the claimed design.

The dot dash line is included for the purpose of illustrating the bounds of the enlarged view and forms no part of the claimed design.
